Des. 323

Joseph G. Lamb of Cincinnati Ohio.
Letters Patent No 323. Dated Sept. 24. 1850.

The Schedule referred to in these Letters Patent and making part of the same.

To all whom it may concern.

Be it known that I, Joseph G. Lamb, of Cincinnati, County of Hamilton and State of Ohio, have invented or produced a new Ornamental Design for Premium Cooking Stoves, and I do hereby declare that the following is a full & exact representation & description of the same To wit.

Figure 1, of annexed Drawings shows a complete view of the Back of Stove with the Top, Cornice, Base & corner mouldings, also the panel with ornamental corners in center. Figure 2, is a side view of Stove complete. Figure 3, is a correct view of the front of Stove. Figure 4, Foot. Figure 5, full size of mouldings on top & upper side of Body of Stove. Figure 6, Base moulding around body of Stove. Figure 7, Corner mouldings. Figure 8, moulding around front hearth.

What I claim as new & my invention, is the combination & arrangement of the above represented & described mouldings, shapes, figures & ornaments into the above represented Design for Cooking Stoves, substantially as above shown.

Witnesses.
